UNITED STATES PATENT OFFICE

164,289

AMPLIFIER

William C. De Vry, Chicago, Ill., assignor to De Vry Corporation, Chicago, Ill., a corporation of Illinois

Application August 18, 1950, Serial No. 11,822

Term of patent 7 years

(Cl. D26—5)

To all whom it may concern:

Be it known that I, William C. De Vry, a citizen of the United States, and a resident of Chicago, in the county of Cook, and State of Illinois, have invented a new, original, and ornamental Design for an Amplifier, of which the following is a specification, reference being had to the accompanying drawings forming a part thereof, and in which:

Fig. 1 is a perspective view of an amplifier in closed condition, showing my new design; and

Fig. 2 is a perspective view of the same in open condition.

I claim:

The ornamental design for an amplifier, as shown.

WILLIAM C. DE VRY.
